Arlington E. Hemp, Burkittsville, Md.

Application May 4, 1946, Serial No. 129,313

Term of patent 14 years

(Cl. D86—10)

To all whom it may concern:

Be it known that I, Hazel May McCalla, a citizen of the United States, residing at Frederick, in the county of Frederick, State of Maryland, have invented a new, original, and ornamental Design for a Stand and Appliance Support for Dressing Hair, of which the following is a specification, reference being had to the accompanying drawing, forming part thereof.

Figure 1 is a perspective view of a stand and appliance support for dressing hair showing my new design; and Fig. 2 is a top plan view thereof.

I claim:

The ornamental design for a stand and appliance support for dressing hair, as shown.

HAZEL MAY McCALLA,
